UNITED STATES PATENT OFFICE

ALFRED TROSCH, OF ROCHESTER, NEW YORK, ASSIGNOR TO CONSOLIDATED MACHINE TOOL CORPORATION OF AMERICA, OF ROCHESTER, NEW YORK, A CORPORATION OF DELAWARE

CRANK PLANING MACHINE

Application filed May 3, 1926. Serial No. 106,439.

This invention relates to a crank planing machine in which a work table has a quick return motion, and the object is to provide a crank planer with practical and simple means that will permit successful cooperation between a tool and one or both sides of the work, as well as the top thereof.

Another purpose of the invention is to so construct a machine of the type mentioned as to enable locating a tool-head to one or both sides of and in spaced relation to a work table.

Still a further object of the invention is to afford mechanism in conjunction with a crank planer for simultaneously feeding tool-heads located respectively above and to one side of the work for cooperation with the top and sides thereof, such feeding being effected simultaneously and in a predetermined relation.

With these ends in view, the invention comprises the construction that will appear clearly from the following description when read in conjunction with the accompanying drawings, the features of novelty being pointed out in the claims following the description.

In the drawings:

Figure 1 is a front elevation of a conventional crank planer having applied thereto one embodiment of the invention;

Figure 2 is a side elevation of the same, and

Figure 3 is a horizontal sectional view taken on the line indicated generally at 3—3 of Figure 2.

Referring more particularly to the drawings in which like reference numerals refer to the same parts in different views, 1 designates a base or bed upon which is mounted a work table 2 for reciprocating movement with relation to the tools. The work table 2 is given a quick return movement through the action of crank mechanism that is controlled from the motor 3 and operatively connected with the work table through parts such as are well known in the art and therefore unnecessary to illustrate in detail.

4 and 5 designate uprights or standards upon which is mounted for vertical adjust-

ment the crossrail 6 having a tool-head 7 movable thereon and adapted to support a tool for cooperation with the upper surface of the work. The upright 5 extends to a point beneath the top of the work table, and is spaced laterally at one side thereof. The standard 5 is adapted to receive a side tool-head 8 which can be fed vertically on the standard 5 beneath the crossrail, and is movable to a position beneath the top of the table, as illustrated in Figure 1 so as to bring its tool into cooperative relationship with a side of the work, this arrangement permitting simultaneous operation upon the top and side of the work. Under such conditions it is desirable to provide for simultaneously feeding both the top and side tool-heads, and this is accomplished by the following mechanism.

The crank shaft, which effects movement of the work table, is provided with a crank 10, see Figure 2, and crank arm 11 connected to one end of a rocker arm 12. The rocker arm 12 is pivoted at 13 and has its opposite end 14 connected to an actuating device preferably comprising a vertically arranged reciprocating rack 15 which cooperates with a suitable gear forming part of a feed mechanism designated generally at 17 for effecting the necessary lateral feeding of the top tool-head 7 on crossrail 6, through a screw 18.

The side tool-head 8 is fed by a vertical screw 19 extending through the standard 5 which carries at its lower end a bevel pinion 20 engaged by a bevel pinion 21. The latter is controlled through gearing including pinion 22, gear 23, and gear 24, see Figure 3, the gear 24 being engaged and actuated by the aforementioned actuating device or rack 15 at the lower end of the latter. It will be understood that one of the gears in the train just referred to has an operating movement only in one direction, as well known in this type of feeding mechanisms, and that during the operating stroke of the rack 15, the mechanism just described serves to move the side tool-head 8 vertically at the same time that the top tool-head 7 is fed horizontally. The amount of feeding of the respective tool-heads need not necessarily be the same,

though the feeding operation of both take place simultaneously, and by varying the relation of the gears in the respective feeding gear trains, it is possible to impart a greater or less feeding motion to one tool-head than the other.

In order to properly counterbalance the side tool-head 8, a counterweight 25 is provided which is connected thereto by a cable 26 extending around pulleys 27 and 28 and thence downwardly through the opening 29 in standard 5, which serves also to house the aforementioned vertical screw 19.

Although only one side-head has been shown and described, the construction of upright 5 and its side-head 8 may be duplicated for upright 4, affording tools and tool controlling mechanism on both sides of the work table, similar to that already described.

While the invention has been described with reference to a particular arrangement, it is not confined to the precise details herein set forth, but may be modified within limitations without departing from the primary accomplishments of the improvement or the scope of the following claims.

I claim:

1. In a crank planing machine, the combination with a work table and crank mechanism for imparting a quick return movement thereto, said crank mechanism including a crank shaft for controlling movement of the work table, of uprights, a crossrail adjustable on said uprights, one of the uprights extending to a point beneath the top of the work table and spaced laterally therefrom, a tool head movable on the crossrail, a second tool head movable on the last named upright to a point beneath the top of the work table and opposite one side thereof, feeding mechanisms for the tool heads, a common actuating device cooperating with said feeding mechanisms, and a crank on the aforesaid crank shaft operatively connected to said common actuating device.

2. In a crank planing machine, the combination with a work table and crank mechanism for imparting a quick return movement thereto, of uprights, a crossrail adjustable on said uprights, one of the uprights extending to a point beneath the top of the work table and spaced laterally therefrom, a tool head movable on the crossrail, a second tool head movable on the last named upright to a point beneath the top of the work table and opposite to one side thereof, a feed screw arranged vertically in said upright for controlling the last mentioned tool head, feeding mechanism located at the bottom of said upright below the work table and operatively connected to said feed screw, of feeding mechanism for the first mentioned tool head, a common actuating device cooperating with said feeding mechanisms and operating to simultaneously feed the tool heads laterally

and vertically respectively, and operative connecting means between said crank mechanism and said actuating device.

3. In a crank planing machine, the combination with a work table and crank mechanism for imparting a quick return movement thereto, said crank mechanism including a crank shaft for controlling movement of the work table, of uprights, a crossrail adjustable on said uprights, one of the uprights extending to a point beneath the top of the work table and spaced laterally therefrom, a tool head movable on the crossrail, a second tool head movable on the last named upright to a point beneath the top of the work table and opposite one side thereof, a feed screw arranged in said upright for controlling the last mentioned tool head, feeding mechanism located at the bottom of said upright below the work table and operatively connected to said feed screw, feeding mechanism for the first mentioned tool head, a common actuating device cooperating with said feeding mechanisms and operating to simultaneously feed the tool heads laterally and vertically respectively, a crank on the aforementioned crank shaft, and a connection between said crank and said common actuating device.

In witness whereof, I have hereunto signed my name.

ALFRED TROSCH.
